UNITED STATES PATENT OFFICE.

FREDERICK L. CHAPMAN, JR., OF CHICAGO, ILLINOIS.

DOOR-OPERATING MECHANISM.

1,247,504.

Specification of Letters Patent. Patented Nov. 20, 1917.

Application filed March 21, 1917. Serial No. 156,413.

To all whom it may concern:

Be it known that I, FREDERICK L. CHAPMAN, Jr., a citizen of the United States, residing at Chicago, in the county of Cook and State of Illinois, have invented certain new and useful Improvements in Door-Operating Mechanisms; and I do hereby declare the following to be a full, clear, and exact description of the invention, such as 10 will enable others skilled in the art to which it appertains to make and use the same.

This invention relates to a mechanism for opening doors, such as the doors of a garage, gates, or the like, which mechanism is operated by the depression of a lever which is positioned in a roadway, so that a vehicle may be driven thereover, for opening the door of a garage, for opening a gate or analogous structure.

20 Another object of this invention is to provide a door operating structure as specified, which includes a disk, or wheel, to which an arm is eccentrically connected, which arm is in turn connected to the door section so 25 that during the rotation of the disk, the doors will be opened, and further to provide a weight which is carried by a chain and rotates the disk upon release of the disk from engagement with its restraining means, 30 which restraining means is released by the depression of a pedal positioned in the roadway leading to the garage or gate.

With the foregoing and other objects in view, this invention consists in such novel 35 features of construction, combination and arrangement of parts as will be hereinafter more fully described, illustrated in the accompanying drawings and claimed.

In describing the invention in detail, reference will be had to the accompanying 40 drawings wherein like characters designate like and corresponding parts throughout the several views, and in which:—

Figure 1 is a perspective view of a garage, and the portion of the road leading thereto showing the pedal in position;

Fig. 2 is a horizontal section illustrating the door structure in an open position, in plan;

50 Fig. 3 is a vertical section taken on the line 3—3 of Fig. 2;

Fig. 4 is a section through the weight, showing the manner of attaching it to the chain;

55 Fig. 5 is a fragmentary vertical section, illustrating a rod for manually operating

the door opening mechanism independent of operation of the tread structure;

Fig. 6 is a detail section showing the tread 60 in end elevation;

Fig. 7 is a section taken at right angles to Fig. 6;

Fig. 8 is a fragmentary side elevation of a modified form of the invention;

Fig. 9 is a vertical section through part 65 of the modified form of the invention showing the remainder in edge elevation.

Referring more particularly to the drawings, 1 designates a garage, of any ordinary construction, which has doors 2 and 3. The 70 doors 2 and 3 are constructed of a plurality of hingedly connected sections 4 and 5 as clearly shown in Fig. 2 of the drawings, and if it is so desired, suitable rollers or analogous guiding members indicated at 6 may 75 be carried by the upper inner corners of each of the door sections 5 for guiding the movement of the door sections. The door sections 5 are hingedly connected to the door sections 4 by hinges 7, while the sections 4 80 are hingedly connected as shown at 8 to the body or garage structure. The door sections 4 of the door 2 have a rod 10 connected thereto, which rod is connected through the medium of a pivotal joint 11 to an arm 12. 85 The arm 12 is secured to a disk 14 eccentrically of the center of the disk as indicated at 15 so that when the disk is rotated, the arm 10 will be operated for moving the door sections 2 into an opened position as indicated in Fig. 2 of the drawings.

The door section 4 of the door 2 has an arm 16 connected thereto and positioned beneath the door sill, to which arm a link 17 is connected. The link 17 is connected as 95 shown at 18 to an arm 19 which is connected to the section 4 of the door 3 for moving the sections 4 and 5 of each of the doors 2 and 3 in unison upon the rocking movement of the arm 10.

The disk 14 is rotatably supported by a pin 20 which pin is in turn supported by a suitable bracket 21. The disk 14 has a pair of diametrically opposed notches 22 formed in its periphery, in which notches the head 105 23 of a pawl 24 is adapted to seat for restraining rotary movement of the disk. The pawl 24 is pivotally mounted upon a pin 25, as clearly shown in Fig. 3 of the drawings, and it has a coupling 26 connected to its end 110 remote from the head 23.

The coupling 26 has a rod 27 adjustably

connected thereto by means of screw threads as shown at 28. The rod 27 extends downwardly, through the horizontal portion 29 of an angle bracket 30, and it has a collar 31 mounted thereon against which one end of a coiled spring 32 engages. The other end of the coiled spring 32 engages the under surface of the horizontal portion 29 and the spring tends to hold the rod 27 downwardly for moving the head 23 of the pawl 24 into one of the notches 22.

The disk 14 has teeth 33 formed upon its periphery, which teeth mesh with the links 34 of a chain 35 which chain hangs downwardly from the disk as clearly shown in Fig. 3 of the drawings. A weight 36 is provided which has a vertically extending opening 37 formed centrally therein through which the chain 35 extends. A pair of upwardly standing eyes 38 are carried by the weight 36 and a pin 39 is inserted through the eye 38 and one of the links 34 of the chain 35 for connecting the weight 36 to the chain.

When the pawl 24 is pivotally moved for moving the head 23 out of one of the notches 22, the weight 36, will, in moving downwardly, rotate the disk 14, which will operate the arm 10 for moving the door sections 4 and 5 of the door 2 into an open position and the movement of the door sections 4 and 5 of the door 2 will through the connection of the arms 16, link 17 and arm 19, move the door sections 4 and 5 of the door 3 into an open position.

The rod 27 is moved vertically, for rocking the pawl 24, by the depression of a pedal 40 which is positioned in one of the tracks of a roadway indicated at 41, which leads to the garage 1. The pedal 40 is carried by a bell crank 42 which is pivotally mounted as shown at 43 within a box 44 which box is embedded in the road bed. A suitable cover plate 45 is provided for the box 44. The bell crank 42 has a rod 46 pivotally connected thereto as shown at 47 which rod extends under ground, to beneath the sill indicated at 48, of the door structure, where it is connected to the bell crank 49. The bell crank 49 is pivotally mounted as shown at 50 within a box 51. The arm 52 of the bell crank 49 is connected to the lower end of the rod 27 so that upon the depression of the pedal 40, by a vehicle passing thereover, the rod 27 will be moved upwardly, through the medium of the bell cranks 42 and 49 and the rod 46, for releasing the disk 14 from the restraining action of the pawl 24, after which the disk will be rotated, by the weight 36 falling downwardly which rotation will open the doors as previously described.

The rod 27 has a handle 53 attached thereto at a convenient height from the ground, to be reached by the hands of a person, which rod extends through an opening 54

formed in one side of the garage 1. The opening 54 is of sufficient length to permit the rod 27 to be moved vertically, manually, for manually releasing the disk 14 from the restraining action of the pawl 24, when it is desired to open the door and enter the garage on foot. A lock structure of any desired type, as indicated at 55 may be provided for locking the rod 53 against movement, and consequently locking the rod 27 against movement, which will prevent the opening of the doors.

After the doors have been opened, they are closed manually and the device is reset by removing the pin 39, and raising the weight 36 upwardly to the upper end of the vertical run 35' of the chain 35. The rod 27 is moved into its normal position by the spring 32.

In Figs. 8 and 9 of the drawings, a modified form of the invention is shown, which is constructed so that the device may be reset by pulling downwardly upon the run of the chain which is positioned upon the opposite side of the center of the sprocket 90 over which the chain travels, from the weight.

In the modified form, a disk 60 is provided, which is mounted upon a shaft 61. The disk 60 has a rod 62 connected thereto as shown at 63. The rod 62 corresponds to the disk and is provided for operating the door sections. The disk 60 is provided with notches 64 formed in the periphery thereof, corresponding to and serving the same function as the notches 22. The disk 60 has an angularly disposed annular flange 65 formed above the periphery of the same, which overhangs the ratchet 66. The ratchet 66 is also mounted upon the shaft 61 and connected to the disk 60 through the medium of pawls 67. The pawls 67 are pivotally connected as shown at 68 to the inner circumference of the flange 65 and they engage the peripheral notches of the ratchet 66 for connecting the ratchet to the disk. A sprocket wheel 69 is also mounted upon the shaft 61 and it is connected to the ratchet 66 for rotation therewith. The chain 70 passes about the sprocket 69 and it has a weight 71 mounted thereon. The chain 70 is identical with and serves the same function as the chain 35 while the weight 71 is identical with the weight 36.

In the modified form of the invention, when it is desired to reset the device, the run 72 of the chain, which is positioned upon the opposite side of the center of the sprocket 69 from the run of the chain to which the weight 71 is connected, is pulled downwardly and since the sprocket is connected to the disk 60 only through the medium of the pawl 67, the weight may be pulled upwardly to the upper limit of its movement without rotating the disk 60, owing to the

fact that the pawl 67 will ride over the ratchet teeth of the ratchet 66.

From the foregoing description taken in connection with the accompanying drawings 5 the advantages of construction and of the method of operation of the improved stay bolt will be readily apparent to those skilled in the art to which this invention appertains, and, while in the foregoing description 10, the principle of the operation of this invention has been described together with various features of construction, it is to be understood that certain minor features of construction, combination and arrangement 15 of parts may be altered to suit practical conditions provided such alterations are comprehended within the scope of what is claimed.

What is claimed is:—

- 20 1. In a door operating structure, the combination, with a door, of a rotatably mounted disk, means for restraining rotation of said disk, an arm eccentrically connected to said disk, a rod pivotally connected to said arm and to said door for moving said door into an open position upon rotation of said disk, means for rotating said disk upon movement of said restraining means into an inoperative position, a pedal, and means operable by the depression of said pedal for moving said restraining means into an inoperative position.
- 25 2. In a door operating structure, the combination, with a door, of a rotatable disk, an arm eccentrically connected to said disk, a rod pivotally connected to said arm and to said door for moving said door into an open position upon rotation of said disk, peripheral teeth formed upon said disk, a chain for engagement with said teeth, a weight carried by said chain for moving the chain for rotating said disk upon release of the disk from said restraining means, a pedal, and means operated by the depression of
- 30 35 40

said pedal for moving said restraining means into an inoperative position.

3. In a door operating structure, the combination, with a door, of a rotatable disk, an arm eccentrically connected to said disk, a rod pivotally connected to said arm and to said door for moving said door into an open position upon rotation of said disk, peripheral teeth formed upon said disk, a chain for engagement with said teeth, a weight carried by said chain for moving the chain for rotating said disk upon release of the disk from said restraining means, a pedal, means operated by the depression of said pedal for moving said restraining means into an inoperative position, and means for moving said restraining means into an operative position immediately after the release of pressure from said pedal.

4. In a door operating structure, the combination, with a door, of a rotatable disk, an arm eccentrically connected to said disk, a rod pivotally connected to said arm and to said door for moving said door into an open position upon rotation of said disk, peripheral teeth formed upon said disk, a chain for engagement with said teeth, a weight carried by said chain for moving the chain for rotating said disk upon release of the disk from said restraining means, a pedal, means operated by the depression of said pedal for moving said restraining means into an inoperative position, means for moving said restraining means into an operative position immediately after the release of pressure from said pedal, and means for manually removing said restraining means into an inoperative position.

In testimony whereof I affix my signature in presence of two witnesses.
